CAN OPENER

Robert C. Gabriel and Frank C. Friend,
Decatur, Ill.

Application January 16, 1950, Serial No. 138,784

4 Claims. (Cl. 30—6.1)

1

The present invention relates to can openers and particularly to a can opener for puncturing openings in a can top.

It is an object of the present invention to provide a can opener for mounting on a wall, cabinet or table, whereby two holes may be punched simultaneously therein by a single lever.

Another object is to provide a can opener comprised of a minimum number of working parts thereby producing an economically manufactured and very durable product.

Still another object is to make a can opener from parts which may be made on a mass production basis so as to further make it possible to sell the same at a very low price.

The above and other objects of our invention will appear from the following specification in which one embodiment of the same is described and illustrated in the accompanying drawings, wherein:

Figure 1 is a side elevation view showing our novel can opener in full line and a can to be opened in dotted line with actuating means thereof shown in solid line in its inactive position and in dotted line in its active position to open the can.

Figure 2 is a front elevation of the can opener.

Figure 3 is a top plan view of the same.

Figure 4 is a bottom plan view thereof.

Figure 5 is a plan view partly cross section taken on the line 5—5 of Figure 1.

Figure 6 is a perspective view of the can raising plate.

Figure 7 is a side elevation view showing one of the piercing members shown supported by the main body of the can opener.

Figure 8 is a front elevation view showing the actual cutting edge of one of the piercing members.

Referring to the drawings in detail and first with particular reference to Figs. 1 and 2, there is shown an integrally formed C-shaped body B. This body B comprises a flat base 10 formed with an aperture 11 centrally therethrough. Depending from the bottom of the base on each side of the aperture 11 are apertured lugs 13 and 14 respectively. These lugs are arranged so that their respective apertures are in alignment on each side of the aperture 11.

Mounted in the aperture 11 between the lugs is a can raising plate unit 15. This plate unit comprises a flat disc-like portion 16, which is formed with the depending shaft 17, which shaft slidably engages the aperture 11, the bottom of said shaft 17 thus engaging in cam action the

2

curved cam surface 18' of the head 18 of the lever 19 which is mounted between the lugs 13 and 14. This lever 19 comprises an elongated handle portion 19' which is curved to conform to the palm of the operator's hand, and the head 18 of the lever 19 is adapted to form a can raising cam to move upwardly the plate unit 15, thus to raise the can which may be placed on the plate unit 15.

The cam head 18 and cam surface 18' curves off-center with respect to the curved axis of the operating handle 19'. Through the axis of the curved handle 19' there is a transversely extending opening 20, see Figs. 1 and 2. In this opening 20 of the cam, which is adapted to align with the apertures of the lugs 13 and 14 positioned on each side of the aperture 11 in the base 10 there is a transverse pivot pin 20'. The can raising plate 15 is shown separated from the rest of the device in Fig. 6 and in position to show its shank 17 in engagement with the surface 18' of the cam head 18 between the lugs 13 and 14 in Fig. 2 of the drawings.

Extending vertically upward from the rear of the base 10 is a vertical guide member 21. The guide member 21 is curved transversely interiorly to conform to the curve of a can 22 to be opened and it is thus guided along its extended longitudinal surface as hereinafter explained more fully.

The guide 21 is sufficiently elongated to extend beyond the length of the cans 22, which are to be opened and is formed with countersunk openings 23 and 24 to receive the heads of screws for fastening the same to a cabinet, table, wall or the like. The top 25 of the vertical guide 21 forms the top of the L-shaped body B and overhangs the can supporting base 10 of the body.

This top 25 is formed with a T-head portion, each ear 26 and 27 of which supports one of a pair of can opening members 28 and 29. The can opening or piercing members may be formed from the T-head or be detachably connected as by screws 30 and 31, see Figs. 1 and 3.

The piercing members 28 and 29 are made with cutting edges 32, see Figs. 7 and 8, as shown are formed with threaded sockets for detachment if they need sharpening or replacement. Also, the rear peripheral edge of the base 10, adjacent each side of the vertical guide 21, is formed with a gage flange 33. This gage flange serves to center or properly position the base of the can 22 on the base 10 with respect to the piercing members 28 and 29.

Operation

To pierce a can, it is placed upon the plate por-

tion 16 of the can raising unit 15 and is pushed back against the guide 21. The handle 19' is kept first in the down position shown in Fig. 1.

After the can is in position it is held pressed against the guide 21 by hand and the handle 19' is pulled up as shown in the dotted line position in Fig. 1. This causes the cam surface 18' to push upward on the bottom of the shank 17 of the unit 15 to raise the same and project the can top into the piercing members 28 and 29. After this the can is removed in its opened or pierced condition.

Without further description it is believed that the foregoing thoroughly explains our invention and its novel parts, arrangement and combinations thereof. While the device has been described specifically for only one form thereof, it is to be expressly understood that other arrangements and combinations of the parts now likely to occur to others are also to be considered a part hereof. To determine the scope of our invention reference should be had to the appended claims.

In which we claim:

1. A can opener having a C-shaped body comprising a base, a vertical guide from the base curved to conform to the wall of a can, a T-head overhanging the base, a pair of piercing members mounted in each arm of the T-head, said base being formed with an aperture, a plate mounted slidably in said aperture, a cam head pivoted to 30 swing beneath the base and engage the plate, a handle for swinging the cam beneath the plate to act on the can to raise it to be opened by the piercing members.

2. A can opener having a C-shaped body comprising a base, a centering flange around a part of the base, a guide extending upward at substantially right angles to the base to guide a can, and a pair of piercing members overhanging the said base, said piercing member being detachable for replacement, and plate and cam means

for moving a can from the base into position to be pierced by the said piercing members.

3. A can opener having a C-shaped body comprising a base, an aperture centrally through the base, a centering flange around a part of the base, a guide extending upward at substantially right angles to the base to guide a can, a pair of piercing members overhanging the said base, a plate mounted in the aperture in the base, a cam lever pivoted to the base for raising the plate to move a can from the base into position to be pierced, said lever being curved to conform to the user's palm.

4. A can opener having a C-shaped body comprising a base, an aperture centrally through the base for mounting a plate member, a centering flange around a part of the base, a guide extending upward at substantially right angles to the base to guide a can, a pair of piercing members overhanging the said base, a disc-like plate above the base, a depending shank centrally on the plate and adapted for sliding engagement in the aperture in the base, an operating lever having a cam on its upper end, said cam being positioned off-center with respect to the axis of the said lever and arranged to engage the bottom of the depending shank on the plate to thereby provide for extra leverage to raise a can to opening position.
